BRAID OR CORD POSITIONING DEVICE FOR
SEWING MACHINES

Albert G. Ferris, Seattle, Wash.

Application August 1, 1949, Serial No. 107,898

2 Claims. (Cl. 112—139)

1

This present invention relates to sewing machine attachments and more particularly to an attachment intended for use with the usual presser foot and it is so arranged that it accurately positions the cord or braid and at the same time secures the attachment in accurate position, even though there be some variation in the exact construction of the presser feet with which it is used.

A large number of attachments have been provided for sewing machines in the past, having as their purpose the positioning of cord or braid and to assist in the sewing of the same in place on material. As a general rule these devices do not adequately serve their intended purpose. In the first place, it is essential that a device of this order be accurately positioned with respect to the line of stitching so that it in turn can accurately position the cord or braid but as sewing machines habitually last a long time, the minor changes made, even in standard lines of production, are such that no one form of observed attachment will adequately adjust to insure a definite and accurate positioning of the positioning device. In the present invention, it is believed that this objection has been overcome and a device produced that is very simple to make, and, which can only be secured on a presser-foot in an accurately positioned manner.

The principal object of this present invention therefore is to provide an inexpensive braiding attachment, which is adaptable for use with the convention presser-foot found on the average sewing machine.

A further object of this invention is to provide a braiding attachment which is resiliently self-centered in the needle slot of a presser foot, so as to insure its accurate positioning at all times and thus make it possible to accurately stitch braid in place.

A further object of this present invention is to provide a braiding attachment for the conventional presser foot, which in no way interferes with the normal functioning of the presser foot, or the feed mechanism disposed immediately below it, and which is so constructed that the braid or cord can be very quickly threaded through the same, and then because of its ability to self-center itself on the presser foot and its resilient clamp arrangement, it can be easily secured on the presser foot.

Further objects, advantages and capabilities will be apparent from the description and disclosure in the drawings, or may be comprehended or are inherent in the device.

In the drawings:

Figure 1 is a perspective view of a conventional sewing machine presser foot and needle assembly showing this present invention secured on the presser foot.

2

Figure 2 is a cross-sectional view taken in the plane of line 2—2 of Figure 1.

Figure 3 is a vertical cross-sectional view taken along the stitching axis of a conventional sewing machine.

Figure 4 is a fragmentary perspective view showing the underside of a presser foot, with the cording attachment shown generally in the position of threading the braid through the device, preparatory to assembling the unit for use with certain parts being shown in section.

Referring more particularly to the disclosure in the drawings, the numeral 10 designates a conventional form of presser-foot, which is held in position and actuated by means of the presser bar lifter 12. Associated with the presser-foot is the sewing machine needle 14, positioned by the mechanism of the sewing machine for vertical reciprocation and passing through the presser-foot slot 16. Normally disposed immediately below the area covered by the horizontal portion of the presser-foot, as 18, is the ratchet feed, all of these elements being conventional and supplied with the usual sewing machine. Experience has proven that any attachment to function with ease and exactness should not disturb any of these elements and their functional relationship with each other, and as a consequence this present invention is so arranged as to use all of these elements without, in any way, modifying their functions.

This present attachment is formed, preferably, of a single piece of resilient sheet stock, of thin enough gauge so that the resilient character of the material can be fully made use of. The attachment is fully secured to the angularly disposed portion of the presser-foot, which normally consists of the two leg elements, as 20 and 21. The attachment is provided with a downwardly extending feed portion 30, which forms a centering means for the attachment, and, also a guide for the braid or cord.

To properly perform its intended function this guide and centering means must have very appreciable extent longitudinally of the stitching plane. It is then provided with the flat top portions as 32 and 33, extending on opposite sides of the V portion 30, and extending outwardly therefrom sufficiently to fully over-lay any of the conventional presser-feet. These members are then turned downwardly to provide the side-walls as 35 and 36, and then have in-turned or reverse bent portions, as 38 and 40. The inside spacing between walls 32 and 38, and 33 and 40 are normally the same, and should be slightly in excess of the thickness of tongues 20 and 21. These various parts have a definite co-action among them, first of all, V 30 must have sufficient transverse extent so that it will bear on the inner margins of tongues 20 and 21 or, in other

words, be sufficiently extended so that the V will never fully seat within groove 16. This will mean that the inner surfaces of legs 32 and 33 normally will not bear upon tongues 20 and 21, but that the inner surfaces of the inturned ends 38 and 40 will be in resilient contact with the bottom surfaces of tongues 20 and 21 after the showing of Figure 2, and thus definite positioning is provided for the attachment. The V must have considerable longitudinal extent so that it will accurately position the V in slot 16, and then, due to the resiliency of the material of which the attachment is made, the V is secured in the slot 16, by the reaction of the inner surfaces of ends 38 and 40. It will follow that, normally, the inner surfaces of the vertical portion 35 and 36 will not bear on tongues 20 and 21. This is an optimum condition which should be achieved in order that, on one hand, the device will fit a large number of slightly modified presser-feet, and on the other hand, it can be easily removed and replaced with the assurance that at every replacement, the V will come to rest at the same position and accurately align the braid or cord with the travel of needle 14.

In order to provide an adequate guide for braid B, the braid must rest within V 30, as is shown throughout the various views, and it must be retained generally therein, by means which permit the easy insertion and removal of the device may be obscured or lost.

As a keeper for braid B, there is provided the generally horizontally disposed plate or keeper 42, which extends well over the center of V 30, as will be noted probably best in Figure 2, and then has a vertical portion as 44, which finally terminates in a second substantially horizontal portion 46 forming a foot plate. This arrangement provides a definite keeper for braid B, and it provides in the member 46, an additional preliminary presser-foot, so as to smooth out any large wrinkles in the material to which the braid is being secured. It also serves as a safeguard for any materials which might otherwise become tangled in the braider, and for this reason it has been found desirable that the auxiliary presser plate 46 be disposed appreciably below the bottom of the normal presser-foot tongues 20 and 21.

The second purpose of the braid keeper is to provide a convenient means of threading the braid through the attachment. This is achieved by the spacing of plate 42, from plate 32 by a slot 48, of a width normally greater than any of the braid or cord that may be used with the device. With such an arrangement it will be apparent that by removing the attachment, after the showing of Figure 4 and twisting it slightly, it can easily be arranged for the braid B to pass in slot 48 and by proper manipulation come to rest under plate 42, and, within the V 30 then, by having the cord, as would normally be desirable, within slot 16 of the presser-foot, it is only necessary to slide the attachment into its position of use on the presser foot and the operator is ready to proceed with the stitching. Any time it is desirable to withdraw the cord from the device, a reversal of this procedure effects the operation very conveniently. With the braid B entered in slot 16 and extending upwardly, it can easily be threaded into using position with the device in place on the presser foot.

It will be apparent, it is believed from the fore-

going description and by a perusal of the accompanying drawings, that an attachment is provided which is simple in use, is resiliently adaptable to a wide range of presser-feet and which is automatically centered and locked on the foot in the accurately aligned position required for proper operation.

What I claim is:

1. A cording and braiding attachment for use on the presser foot of a sewing machine, consisting of: a single piece of resilient metal having an axially aligned positioning and guiding V, with a cord receiving portion, disposed with the open side of said V uppermost; substantially horizontal top plates extending outwardly from each side of said V; downwardly directed side plates continuing from said top plates; inwardly directed clamp plates continuing from said side plates, disposed parallel to said top plates; said clamp plates adapted to co-act with said V to position said attachment to a presser foot and secure it thereto; a keeper, disposed in longitudinal spaced relationship to said V, having a top portion in the same plane as said top plates and extending transversely beyond the cord receiving portion of said V; a downwardly positioned extension of said keeper and a foot plate secured to said keeper extension and disposed parallel to said clamp plates and below the plane of said clamp plates.

2. A cording and braiding attachment for use on the slotted presser foot of a sewing machine, consisting of: a single piece of resilient metal having an axially aligned positioning and guiding V, with a cord receiving portion, disposed with the open side of said V uppermost; said V having greater transverse width than the slot in the presser foot it is associated with; substantially horizontal top plates, extending outwardly from each side of said V; downwardly directed side plates continuing from said side plates; inwardly directed clamp plates continuing from said side plates, disposed parallel to said top plates; said clamp plates adapted to co-act with said V to position said attachment to a presser foot and secure it thereto; a keeper, disposed in longitudinal spaced relationship to said V thereby providing therebetween a transverse slot, having a top portion in the same plane as said top plates and extending transversely beyond the cord receiving portion of said V; a downwardly positioned extension of said keeper and a foot plate secured to said clamp plates and below the plane of said clamp plates.
